CASE FOR PRECISION TOOLS

Ernst E. Thoms, Dayton, Ohio

Application July 31, 1956, Serial No. 42,467

Term of patent 14 years

(Cl. D58—12)

Fig. 1

Fig. 2

Fig. 3

Fig. 4

Fig. 5

Fig. 6

Fig. 1 is a top perspective view of a case for precision tools shown in open position and showing my new design;

Fig. 2 is a front elevational view thereof shown in closed position;

Fig. 3 is a side elevational view thereof shown in closed position;

Fig. 4 is a bottom plan view thereof shown in closed position;

Fig. 5 is a top plan view thereof shown in closed position; and

Fig. 6 is a view in cross section taken substantially along the line 6—6 of Fig. 2.

I claim:

The ornamental design for a case for precision tools, as shown.
